UNITED STATES PATENT OFFICE.

JOHN LINDSAY THOMPSON, OF CINCINNATI, OHIO, ASSIGNOR TO MARGRAF, FRICKE & CO., OF SAME PLACE.

WIND-WHEEL.

SPECIFICATION forming part of Letters Patent No. 571,056, dated November 10, 1896.

Application filed June 19, 1896. Serial No. 596,204. (No model.)

To all whom it may concern:

Be it known that I, JOHN LINDSAY THOMPSON, a citizen of the United States, residing at Cincinnati, in the county of Hamilton and

5 State of Ohio, have invented certain new and useful Improvements in Wind-Wheels, of which the following is a specification.

My invention relates to improvements in wind-wheels of the horizontal type; and it 10 consists in the novel features of construction hereinafter fully described, and particularly pointed out in the claims.

In the accompanying drawings, Figure 1 is 15 an elevation of the wind-wheel embodying my invention, showing the vertical shaft on which it is mounted broken off; and Fig. 2, a plan of the same, the arrows showing, respectively, the direction in which the wheel is rotating and that of the wind or turning force. Both 20 these views show the wheel as it appears in motion.

a represents the vertical shaft adapted to be mounted on a staff, mast, barn, tower, or elsewhere to suit the surroundings or the work 25 to be performed by the wheel, which latter is suitably mounted on said shaft and is composed of the elements that I will now describe.

b b' are flanged hubs keyed to shaft *a* at a suitable distance apart at its top or upper 30 end, *c c c c* radial eyes constructed on said hubs, and *d d d d* horizontal V-shape brackets or open frames comprising tangential rods or arms whose inner diverging ends engage the eyes *c'* and are detachably connected 35 thereto by means of nuts and whose outer converging ends engage eyes *d'* on the coupling and reinforce plates *C*, and are also detachably secured by means of nuts.

e e e e represent segmental rim-sections 40 detachably connected together (to form a continuous circular series or a rim) by means of the coupling-plates *C* and bolts *C'*.

e' represent angular bends or recesses in 45 said rim-segments *e* to form receptacles for the free ends 1 of the blades or fan-paddles *B* when thrown open. The blades *B* are pivoted or hinged to the rim-segments *e* by means of pins *p* and plates or brackets *p' 2*, and the outer ends *B'* of said blades are curved or 50 flared toward the wind, the pivotal end of each blade being notched or open-slotted at

*B*² for the free outward swinging or full and free clearing of the curved portion *B'* beyond the rim *e*.

The arrow *A* indicates the direction in 55 which the wind is advancing and entering into the wheel, and arrow *D* the direction in which the wheel revolves.

The wheel as constructed and being of the horizontal class may be mounted on a tower, 60 barn, or building, as stated, or on a separate mast separate from any structure, and readily connected with a well or pump or other object to be driven, either directly or by means of a horizontal shaft mitered to the vertical 65 shaft, on which latter the wheel is rigidly secured or mounted by keys or otherwise, as hereinbefore mentioned.

The wheel being composed of the elements named, which are detachably connected or 70 united together, is thus a "knockdown" one, conveniently capable of very ready handling at all times, and of being packed in small compass for storing and shipping, and also for making repairs at a minimum of expense, 75 as any part or section can be replaced or handled without disturbing the rest.

In the operation of the wheel (which is clearly seen in the several views) the blades are so mounted and they clear so quickly that 80 they get the full force of the wind or other propelling medium, which is duly utilized, and no lost motion nor dead wind or force occurs in their use. The curved pivotal ends *B'* of the blades present a final face or resistance to the wind as the wheel advances, and after said wind has spent its direct force on the face of a blade this curved end serves to cause the blade to open more quickly and to readily bring it into rest against the received rim.

I claim—

1. A knockdown horizontal wind-wheel composed of a pair of hubs keyed to a vertical shaft; a series of horizontal V-shape 95 brackets or open, skeleton rod-frames detachably secured at their inner, divergent ends to said hubs; a series of segmental rim-sections having receptacles or bent, recessed portions made therein and detachably jointed 100 together in a circle, and detachably mounted, also, at the outer, convergent ends of said

V-brackets; and a series of blades or fan-paddles pivotally mounted on said segmental rim-sections; substantially as herein set forth.

2. In a horizontal wind-wheel, a blade or 5 fan-paddle composed of a plate having its outer pivotal or hinged end curved or flared toward the wind, whereby a prolonged impingement of the wind, and a ready, quick opening or clearing of the blade against the

wheel-rim are effected in the revolutions of 10 the wheel, substantially as herein set forth.

In testimony of which invention I have hereunto set my hand.

JOHN LINDSAY THOMPSON.
